(57) **CLAIM**

The ornamental design for a pot wrap with perforated index card, as shown and described.

DESCRIPTION

FIG. 1 is a plan view of a pot wrap with perforated index card showing my new design, the opposite side being a mirror image;

FIG. 2 is a plan view of a second embodiment of my new design, the opposite side being a mirror image;

FIG. 3 is a plan view of a third embodiment of my new design, the opposite side being a mirror image;

FIG. 4 is a plan view of a fourth embodiment of my new design, the opposite side being a mirror image;

FIG. 5 is a plan view of a fifth embodiment of my new design, the opposite side being a mirror image;

FIG. 6 is a plan view of a sixth embodiment of my new design, the opposite side being a mirror image;

FIG. 7 is a side view of FIGS. 1–6 thereof;

FIG. 8 is a perspective view of FIG. 1, shown in an installed position;

FIG. 9 is a perspective view of FIG. 2, shown in an installed position;

FIG. 10 is a perspective view of FIG. 3, shown in an installed position;

FIG. 11 is a perspective view of FIG. 4, shown in an installed position;

FIG. 12 is a perspective view of FIG. 5, shown in an installed position; and,

FIG. 13 is a perspective view of FIG. 6, shown in an installed position.

The views of the pot wrap with perforated index card not shown form no part of the claimed design. The dotted lines in the figures depicting substantially rectangular shapes represent perforations. The broken lines depicting optional top retaining members, tongue, tongue slot, and index card slots represent environmental elements only and form no part of the claimed design. The separations and brackets indicate, for ease of illustration, that the precise height and width or the precise height and diameter of the pot wrap with perforated index card is not claimed.
